DRYING RACK

Carl F. Smith, Faribault, Minn.

Application June 2, 1945, Serial No. 597,367

3 Claims. (Cl. 211—100)

1

This invention relates to a rack and particularly to a drying rack adapted to be supported in a room such as a bathroom for drying stockings or other articles. It is the common practice for women to wash their stockings, particularly silk and nylon stockings, frequently and it is the common practice to suspend them on supports for drying. There is usually no convenient support for this and as a result stockings are commonly hung on towel racks, door knobs, etc.

It is an object of this invention to provide a very simple and efficient rack which may be conveniently supported in a bathroom or other room and which is capable of easy and quick operation and which will occupy a small space when not in use.

It is a further object of the invention to provide a drying rack comprising a member adapted to be secured to a wall or other support in substantially vertical position, a second member pivoted to said member adjacent one end thereof and adapted to be supported in substantially horizontal position, said second member having a plurality of spaced supports thereon adapted to hold stockings or other articles, said members being collapsible with said supports so that they may be arranged in substantially parallel relation close together when not in use.

It is another object of the invention to provide a device comprising an elongated casing which is open at its front side and adapted to be supported in substantially vertical position, a member pivoted to said casing adjacent one end thereof and being swingable to substantially horizontal position, said member being constructed and arranged to be held in substantially horizontal position, the same having a plurality of spaced supports secured thereto and adapted to depend therefrom for supporting stockings or other articles, said member and supports being swingable into said casing when the device is not in use.

It is more specifically an object of the invention to provide a device comprising an elongated casing of small transverse dimension having an open front side and being arranged to be secured to a wall or other support in substantially vertical position, a bar having an elongated slot adjacent one end, a pivot member extending through said slot and secured in the sides of said casing, said bar being swingable on said pivot to substantially horizontal position and being capable of being moved inwardly in said casing relatively to said pivot, means in said casing engaging the top of said bar to hold it in said

substantially horizontal position, said bar having a plurality of spaced supports pivotally connected thereto and arranged to depend therefrom for supporting stockings or other articles, said bar and said supports being swingable into said casing with said bar preferably having its outer side flush with the sides of said casing and forming a closure therefor.

These and other objects and advantages of the invention will be fully set forth in the following description made in connection with the accompanying drawings in which like reference characters refer to similar parts throughout the several views and in which:

15 Fig. 1 is a perspective view of a device in closed or inoperative position;

Fig. 2 is a view in side elevation of the device in operative position;

Fig. 3 is a vertical section taken substantially on line 3—3 of Fig. 7, as indicated by the arrows;

Fig. 4 is a perspective view of a portion of a bar used;

Fig. 5 is a vertical section similar to Fig. 3 showing the parts in a different position;

25 Fig. 6 is a central vertical section through the device;

Fig. 7 is a vertical section taken on line 7—7 of Fig. 5, as indicated by the arrows;

Fig. 8 is a horizontal section taken on line 8—8 of Fig. 6, as indicated by the arrows;

Fig. 9 is a horizontal section taken on line 9—9 of Fig. 6, as indicated by the arrows; and

Fig. 10 is a view in front elevation of a link used.

Referring to the drawings, a drying device is shown comprising a casing 20 which may conveniently be formed of wood or other material, and while this casing might take various forms, in the embodiment of the invention illustrated it is shown as substantially rectangular in transverse cross section and quite elongated in length. Said casing has a rear wall 20a, side walls 20b, a top wall 20c and a bottom wall 20d. Said casing is open at its front side between top and bottom walls 20c and 20d. Said casing is preferably provided with a plurality of holes 20e extending through rear wall 20a adapted to receive screws 21 or other fastening means for attaching the casing to a wall 22 or other suitable support with said casing in substantially vertical position.

40 A pivot pin 24 extends through and between the sides 20b of the casing adjacent one end thereof, which end is shown as the upper end. A bar 25 has an elongated slot 25a formed therein adjacent one end, one end of said bar being disposed between the sides 20b and hav-

ing said pivot pin 24 passing through slot 25a. Bar 25 is thus pivoted to casing 20 and the same may be swung to position substantially perpendicular to the length of casing 20 or to substantially horizontal position. When bar 25 is swung to its horizontal position, pivot member 24 is disposed at the outer end of slot 25a, as shown in Fig. 5. When the bar is swung to horizontal position it may be moved inwardly or toward the casing, the same moving relatively to pivot 24 and the inner end of the bar will have its top surface engaging a means or projection 20f depending from top wall 20c so that bar 25 will be firmly supported in its horizontal position. Bar 25, as shown in Figs. 4 and 8, has a portion 25b of reduced width and a plurality of links 26 are pivotally connected to said portion 25b, the same having end portions passing through holes 25c extending transversely through portion 25b. While links 26 could be variously formed, in the embodiment of the invention they are shown as substantially rectangular in form having spaced end portions 26a which are disposed in the holes 25c. Links 26 are thus pivotally connected to bar 25. The closed or bight portions 26b of links 26 extend through the coils 27a of coiled compression springs 27. Each of the springs 27 has an end portion 27b extending along one side of and across the back of a gripping member 28a, the portion of said end 27b extending across said back being disposed in a groove 28b formed in said gripping member 28a. Each of said springs 27 has another end 27c extending across the side of and across the back of another gripping member 28c, said gripping member 28c having a groove 28d in its back or outer side receiving the part of end portion 27e which extends across said back. The gripping members 28a and 28c are thus held against the coil 27a of spring 27 in opposed relation and are provided with semi-cylindrical grooves 28g fitting about said spring. Gripping members 28a and 28c can be swung about the axis of spring 27 and the same have engaging surfaces 28e at their lower ends and have diverging portions or arms 28f at their upper ends. Members 28 thus form gripping members adapted to hold a stocking or other article between the parts thereof. The members 28a and 28c are normally held with their surfaces 28e in engagement by springs 27. The gripping members 28 thus depend from links 26, which in turn depend from bar 25.

The rack when not in use will occupy the position shown in Fig. 1. At this time bar 25 is disposed with pivot 24 in the outer end of slot 25a and is disposed within the casing 20. The lower end of bar 25 engages the front side of bottom wall 20d which is spaced somewhat from the front of casing 20 so that the outer side of bar 25 is substantially flush with the fronts of sides 20b, as shown in Figs. 1 and 8. The bar 25 thus forms in effect a cover or closure for casing 20. When the rack is to be used, the operator will take hold of the lower end of bar 25 which extends a short distance below bottom wall 20d and will swing the same about pivot 24 to the position shown in Figs. 2, 3 and 5. Bar 25 will now be pushed inwardly or toward casing 20, slot 25a moving relatively to pivot 24, and the inner end of said bar will be disposed under projection 20f. The bar will now be firmly held in its extended position. Since links 26 and the supports or gripping members 28 are pivotally connected they will automatically swing to substantially vertical positions and depend from bar 25. The articles

to be dried or supported can now be placed between the jaws 28a and 28c of members 28 by pressing together the portions 28f. The articles will be firmly gripped by pressure of springs 27. After the articles are dried and removed the rack can again be returned to collapsed or inoperative position. This can be done by merely pulling outwardly on bar 25 until the end of slot 25a engages pivot 24 and then letting the bar swing to vertical position. The members 26 and 28 automatically swing as the bar 25 swings downwardly and move into the casing 20 in the position shown in Fig. 6.

From the above description it is seen I have provided a very simple and highly efficient drying rack. The rack takes up very little room when not in use and can conveniently be secured to the wall of a room such as a bathroom or closet. The device can be nicely finished so that it will fit in with the other bathroom fixtures and have a pleasing appearance. The device can almost instantly be moved from closed to operative position and vice versa. The articles to be dried can be very easily and quickly attached thereto and detached therefrom. The device is quite simple in construction and can be produced to sell at a very reasonable price. The same has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A drying rack for stockings or other articles having in combination, an elongated casing substantially rectangular in transverse cross section and having an open side, a pivot member extending between the sides of said casing adjacent its upper end, a bar having an elongated slot adjacent one end through which said pivot member passes so that said bar is swingable on said pivot member and may be moved to substantially horizontal position, said bar being movable inwardly in said casing with said slot moving relatively to said pivot member, means adjacent the top of said casing engaging the inner end of said bar when so moved to hold it in said substantially horizontal position, a plurality of spaced supporting means pivotally connected to said bar and adapted to depend therefrom when said bar is in horizontal position and to swing to vertical position at the inner side of said bar when said bar is in vertical position in said casing, said bar and supports being swingable and disposable in said casing when said bar is moved outwardly relatively to said pivot member, said supporting means each comprising a clip having jaws spring pressed to closed position and a link for each of said clips pivotally connected at one end to the under side of said bar when in horizontal position and pivotally connected at its other end to said clip.

2. A drying rack for stockings or other articles having in combination, an elongated narrow casing substantially rectangular in transverse cross section and having a top and an open front side, a pivot member extending between the sides of said casing adjacent said top, said top having a depending portion at its rear and in the rear of said pivot, a bar having an elongated slot ad-

5 jacent one end through which said pivot member passes so that said bar is swingable on said pivot member and may be moved to substantially horizontal position, said bar being movable inwardly in said casing when in said horizontal position with said slot moving relatively to said pivot member to bring its end under said depending portion so that it is held in horizontal position, a plurality of spaced supporting means pivotally connected to said bar and adapted to depend therefrom when said bar is in horizontal position and to swing to vertical position at the inner side of said bar when said bar is in vertical position, said supporting means being of less width than said bar so that they are swingable and disposable in said casing when said bar is moved outwardly and swung to vertical position, said bar substantially fitting in said casing and closing the front thereof with said supporting means at the inner side thereof within said casing.

3. The structure set forth in claim 2, said bar having a portion of reduced width at its inner side and said supporting means being pivoted to said portion about axes extending transversely 25 thereof.
